DESIGN FOR A COMBINED BOWLING GAME
DEVICE AND ASH TRAY

John D. Nagel and Walter Lang, Chicago, Ill.

Application October 25, 1946, Serial No. 134,263

Term of patent 14 years

(Cl. D34—5)

To all whom it may concern:

Be it known that we, John D. Nagel and Walter Lang, citizens of the United States, residing at Chicago, in the county of Cook and State of Illinois, have invented a new, original, and ornamental Design for a Combined Bowling Game Device and Ash Tray, of which the following is a specification, reference being had to the accompanying drawing, forming part thereof.

Fig. 1 is a top plan view of the combined bowling game device and ash tray, a portion of the transparent cover member being broken away; and

Fig. 2, a transverse sectional view taken on the line 2—2 of Fig. 1.

We claim:

The ornamental design for a combined bowling game device and ash tray, as shown.

JOHN D. NAGEL.
WALTER LANG.
